(57) **CLAIM**

The ornamental design for an industrial robot arm, as shown and described.

DESCRIPTION

FIG. 1 is a front view of an industrial robot arm in accordance with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof.

The broken lines shown in the drawings represent portions of the industrial robot arm that form no part of the claimed design.

1 Claim, 8 Drawing Sheets
